SAND TESTER PUMP

Filed May 12, 1927

UNITED STATES PATENT OFFICE.

GEORGE F. LE BUS, OF ELECTRA, TEXAS.

SAND-TESTER PUMP.

Application filed May 12, 1927. Serial No. 190,858.

This invention relates to sand tester pumps.

It is customary in drilling oil wells by the rotary method to drill ahead of the main hole with a small drill. When an oil sand is located, the casing is set and the mud and water is bailed from the holes in order to test the sand. However, it is not possible to remove all mud and water by bailing, due to the fact that the high pressure rotary pumps used in rotary drilling forces mud and water into the oil sands.

An object of the present invention is the provision of an economical and positive working pump for producing a suction on oil sands while shutting off mud and water from the sand so that the suction effect is applied to the oil sands only, thus eliminating the practice pipe setting and bailing.

20 A further object of the invention is the provision of a sand tester pump which is operated by raising and lowering the drill pipe so that when the pump is lowered, fluid will be forced from the sand and out through the drill pipe.

A still further object of the invention is the provision of a sand tester pump which is adapted to be reciprocated in an oil well to remove oil sands for testing and in which 30 is employed a movable friction dog to retain a back pressure valve in position to prevent the fluids in the hole from passing into the pump and drill pipe when the pump is being lowered in the hole.

35 This invention will be best understood from a consideration of the following detailed description in view of the accompanying drawings forming a part of the specification; nevertheless it is to be understood that the invention is not confined to the disclosure being susceptible of such changes and modifications which shall define no material departure from the salient features of the invention as expressed in the 40 appended claims.

Figure 1 is a longitudinal section of a sand tester pump constructed in accordance with the principles of my invention,

Figure 2 is a longitudinal vertical section 50 of the pump shown in Figure 1 and in operative position for pumping,

Figure 3 is an enlarged sectional view of the pump with the valves in open position so that the pump may be readily removed 55 from the well,

Figure 4 is a view in perspective of a removable valve seat,

Figure 5 is a view in perspective of a similarly constructed valve seat adapted to have interlocking engagement with the valve seat 60 shown in Figure 4,

Figure 6 is a view in perspective and partly in section of a frictional stop to control the back pressure valve, and

Figure 7 is a view in perspective of the 65 back pressure valve.

Referring more particularly to the drawings, 10 designates a drill stem having threaded engagement at 11 with a plunger body 12. The plunger is slidably mounted 70 in a tubular body member 13 which has a threaded engagement with the main body member 14 as shown at 15.

A sleeve 16 encircles the stem 10, a packer 17 is mounted on the sleeve 16 and is maintained in place by means of a nut 18 threaded on the sleeve 16 and a rib 19 formed integrally with said sleeve 16.

A packing gland or sleeve 20 is threaded onto the lower end of the sleeve 16 and has 80 a recess 21 to receive an internal packer 22, this sleeve has a threaded engagement at 23 with the plunger 12 and the threads are of such a construction, that when the plunger is rotated to the right, said plunger becomes 85 unscrewed from the sleeve 20. This sleeve as shown at 24 is provided with a shoulder which abuts the upper end of the body member 13.

The internal threads 11 of the plunger 90 12 are extended throughout the length of the hollow portion of said plunger and into which are screwed a nut 25 which forms the guide for a valve stem 26. This nut is provided with a plurality of passages 27 95 through which fluid may pass.

A removable valve seat 28 is threaded into the lower end of the plunger 12 and is provided with a passage 29 controlled by a valve 30. A nut 31 screws onto the upper 100 end of the stem 26 and is adapted to limit the downward movement of the valve 30. The valve seat is provided with depending lugs 32 which are spaced in a predetermined relation to receive lugs 33 projecting upwardly from a sleeve 34. Depending from the valve 30 is a guide rod 35 which is movable through a slot 36 carried by the lug 32 which is adapted to be engaged by a nut 37 threaded onto the lower end of a rod 35. 110

The body 13 is threaded onto the upper reduced end 38 of the lower body member 14. The sleeve 34 has external threads which engage with the internal threads 39 of the body member 14. This sleeve as shown at 40 is provided with a valve seat adapted to be engaged by an intermediate valve 41 which carries a stem or guide rod 42 slidably mounted in a nut 43 threaded into the internal threads 39 of the body member 14. A nut 44 on the lower end of the guide rod 42 limits the upward movement of the valve 41 when said nut moves into engagement with the nut 43; the last mentioned nut is 15 provided with passages 45 to permit the flow of fluid from the lower end of the pump to pass the valve seat 40.

A friction stop generally designated by the numeral 46 is adapted to control the upward movement of a back pressure valve 47 as shown more particularly in Figure 6. This stop consists of an annular ring 48 which has a diametrically disposed rib 49. This rib is provided with diametrically disposed passages 50 in which a pair of pins 51 are slidably mounted and a coil spring 52 located at the inner end of the pins is adapted to maintain the pins in projected relation from the outer ends of the passages 50 and extending beyond the outer surface of the ring 48 to engage either an annular groove 53 or an annular groove 54.

The back pressure valve 47 has an upwardly extending stem 55 adapted to be 35 engaged by the frictional stop 46. The valve 47 has grooved depending flanges 56 which are employed by the upper end of a coil spring 57. This coil spring at its lower inner end is seated upon a tubular connection or sleeve 58 which is secured to a perforated intake of the pump. The valve 47 is adapted to engage a seat 59 formed integral 40 with the body member 14.

The packer 60 has its upper end in engagement with the lower end of the body member 14 and its lower end is engaged by a nut 61 threaded onto the connection 58. This packer is only employed when the well is only of a limited depth. When the well 50 has any extended depth, the packer 60 is removed and the packer 17 only is employed. Either packer, however, contacts with the walls of the well and prevents water and mud from the upper portion of the well 55 from entering the oil sands.

The operation of my device is as follows: Before lowering the pump into the well, the frictional stop 46 is placed in engagement with the annular groove 53 and in 60 this position of the stop, the valve 47 remains closed and the fluid, as shown in Figure 1 is prevented by said valve from entering the pump and pipe while the pump is being lowered into the hole. The pump 65 is then lowered to the bottom of the hole

and either packer 60 or 17 is employed to prevent mud and water from above either of the packers from escaping to the oil sands. The packer 60 as has been explained is only employed when the hole is but a few feet deep.

After the packer has been seated, the drill pipe is turned to the right and the threads 23 are unscrewed allowing the plunger to be lowered to the lower end of the body member 13. This time the rod 35 comes in contact with the top of the valve 41 causing said intermediate valve to seat and forcing the friction member 46 downwardly until the pins 51 engage the groove 54. At this time the back pressure valve 47 has been opened, since the member 46 has engaged the stem 55 of the back pressure valve and forced it off of the seat 59. The valve 47 is therefore maintained open while the fluid 80 is being pumped into the well.

After the well has been pumped sufficiently to test the sand, the plunger 12 is lowered until the cooperating lugs 32 engage with the lugs 33 whereby the sleeve 34 is locked for simultaneous rotation with the seat 28 and plunger 12. On turning the plunger to the right, valve seat 28 having a left hand threaded connection with the plunger, screws away from the valve 30, the travel being limited by the stop 36. This operation releases all of the valves and the drill pipe can be removed from the hole allowing the fluid to run back through the pump.

In case the well does not pump sufficiently to force the fluid out at the top and it is desired to see how much or what kind of liquid is in the drill pipe and pump, the drill pipe can be removed with valves 30 and 41 closed, whereby the fluid is maintained in the drill pipe and can be collected by the removal of the pump.

In order to close valves 30 and 41 it is only necessary to rotate the stem in the opposite direction to that which closed the opening of said valves whereby said valve 30 will be moved into position when the pump is lifted, the valve 41 having been closed by the reverse rotation of the stem.

I claim:

1. A sand tester pump comprising a body member, a plunger adapted for sliding movement in the body member, a stem connected with the plunger, a sleeve having a threaded connection with the plunger and adapted to be released from the plunger when the said plunger is rotated in one direction, said plunger being provided with a seat, a valve slidably mounted in the plunger and adapted to normally engage the seat, a spring pressed back pressure valve slidably mounted in the body member, a seat in the body member adapted to be engaged by the back pressure valve, means movable in one

direction for forcing the back pressure valve from its seat, a third valve located between the plunger valve and the back pressure valve and adapted to be opened when the last mentioned means is moved in the opposite direction.

2. A sand tester pump comprising a body member, a plunger adapted for sliding movement in the body member, a stem connected with the plunger, a sleeve having a threaded connection with the plunger and adapted to be released from the plunger when the said plunger is rotated in one direction, said plunger being provided with a seat, a valve slidably mounted in the plunger and adapted to normally engage the seat, a spring pressed back pressure valve slidably mounted in the body member, a seat in the body member adapted to be engaged by the back pressure valve, the body member being provided with spaced annular grooves in the inner wall thereof, a valve operating means having spring pressed pins adapted to engage a groove, said valve operating means adapted to be moved in one direction by the first mentioned valve for causing opening of the back pressure valve.

3. A sand tester pump comprising a body member, a plunger adapted for sliding movement in the body member, a stem connected with the plunger, a sleeve having threaded connection with the plunger and adapted to be released from the plunger when the said plunger is rotated in one direction, said plunger being provided with a seat, a valve slidably mounted in the plunger and adapted to normally engage the seat, a spring pressed back pressure valve slidably mounted in the body member, a seat in the body member adapted to be engaged by the back pressure valve, means movable in one direction for forcing the back pressure valve from its seat, a third valve located between the plunger valve and the back pressure valve and adapted to be opened when the last mentioned means is moved in the opposite direction, the third mentioned valve having a valve seat, cooperative means between the last mentioned valve seat and the plunger valve seat whereby rotation of the plunger will cause the plunger valve seat to be moved out of operative relation with the plunger valve.

4. A sand tester pump comprising a body member, a plunger adapted for sliding movement in the body member, a stem connected with the plunger, a sleeve having threaded connection with the plunger and adapted to be released from the plunger when the said plunger is rotated in one direction, said plunger being provided with a seat, a valve slidably mounted in the plunger and adapted to normally engage the seat, a spring pressed back pressure valve slidably mounted in the body member,

a seat in the body member adapted to be engaged by the back pressure valve, means movable in one direction for forcing the back pressure valve from its seat, means in the body member cooperating with means on the plunger valve seat to release the plunger valve seat to an inoperative position relative to the plunger valve.

5. A sand tester pump comprising a body member, a plunger adapted for sliding movement in the body member, a stem connected with the plunger, a sleeve having threaded connection with the plunger and adapted to be released from the plunger when the plunger is rotated in one direction, said plunger being provided with a seat, a valve slidably mounted in the plunger and adapted to normally engage the seat, said seat having depending prongs, a valve in the body member having a seat, the last mentioned valve adapted to be engaged by the first mentioned valve, the second mentioned valve seat having prongs adapted to engage with the prongs on the plunger valve seat whereby rotation of the plunger will cause movement of the valve seat in the plunger to an inoperative position relative to the plunger valve for maintaining the plunger valve in open position.

6. A sand tester pump comprising a body member, a plunger adapted for sliding movement in the body member, a stem connected with the plunger, a sleeve having threaded connection with the plunger and adapted to be released from the plunger when the plunger is rotated in one direction, said plunger being provided with a seat, a valve slidably mounted in the plunger and adapted to normally engage the seat, said seat having depending prongs, a valve in the body member having a seat, the last mentioned valve adapted to be engaged by the first mentioned valve, the second mentioned valve seat having prongs adapted to engage with the prongs on the plunger valve seat whereby rotation of the plunger will cause movement of the valve seat in the plunger to an inoperative position relative to the plunger valve for maintaining the plunger valve in open position, a back pressure valve located adjacent the second mentioned valve, a seat in the body member for said back pressure valve, said back pressure valve being adapted to prevent fluid from entering the pump when said pump is lowered into the well.

7. A sand tester pump comprising a body member, a plunger adapted for sliding movement in the body member, a stem connected with the plunger, a sleeve having threaded connection with the plunger and adapted to be released from the plunger when the plunger is rotated in one direction, said plunger being provided with a seat, a valve slidably mounted in the plunger and

adapted to normally engage the seat, said seat having depending prongs, a valve in the body member having a seat, the last mentioned valve adapted to be engaged by the 5 first mentioned valve, the second mentioned valve seat having prongs adapted to engage with the prongs on the plunger valve seat whereby rotation of the plunger will cause movement of the valve seat in the plunger 10 to an inoperative position relative to the plunger valve for maintaining the plunger valve in open position, a back pressure valve located adjacent the second mentioned valve, a seat in the body member for said back 15 pressure valve, said back pressure valve being adapted to prevent fluid from entering the pump when said pump is lowered into the well, and means for releasing and maintaining the back pressure valve from 20 its seat after the pump has been lowered into position.

8. A sand tester pump comprising a body member, a plunger adapted for sliding movement in the body member, a stem connected with the plunger, a sleeve having threaded connection with the plunger and adapted to be released from the plunger when the plunger is rotated in one direc-

tion, said plunger being provided with a seat, a valve slidably mounted in the plunger 30 and adapted to normally engage the seat, said seat having depending prongs, a valve in the body member having a seat, the last mentioned valve adapted to be engaged by the first mentioned valve, the second mentioned valve seat having prongs adapted to engage with the prongs on the plunger valve seat whereby rotation of the plunger will cause movement of the valve seat in the plunger to an inoperative position relative 35 to the plunger valve for maintaining the plunger valve in open position, a back pressure valve located adjacent the second mentioned valve, a seat in the body member for said back pressure valve, said back pressure 40 valve being adapted to prevent fluid from entering the pump when said pump is lowered into the well, means for releasing and maintaining the back pressure valve 45 from its seat after the pump has been lowered into position, the last mentioned means being moved into operative engagement with the second mentioned valve forcing said valve from its seat when the back pressure valve is closed.

GEORGE F. LE BUS.
